C. E. SALLADA,
AIR MOISTENER,
APPLICATION FILED AUG. 2, 1921.

1,425,608.

Patented Aug. 15, 1922.

UNITED STATES PATENT OFFICE.

CLARENCE E. SALLADA, OF HURON, SOUTH DAKOTA.

AIR MOISTENER.

1,425,608.

Specification of Letters Patent. Patented Aug. 15, 1922.

Application filed August 2, 1921. Serial No. 439,290.

To all whom it may concern:

Be it known that I, CLARENCE E. SALLADA, a citizen of the United States, residing at Huron, in the county of Beadle and State 5 of South Dakota, have invented certain new and useful Improvements in Air Moisteners, of which the following is a specification.

The object of this invention is to provide a simple and inexpensive humidifying attachment for hot air furnaces which may be readily fitted to furnaces now in use or supplied with furnaces to be installed. A further object of the invention is to provide a humidifying attachment in which the water to be vaporized may be subjected to the direct heat in the fire-box and may be supplied in any desired quantities. A further object of the invention is to provide a humidifying attachment in which the level of the water may be automatically maintained and in which the overflowing of the water onto the material of the furnace and corroding the joints thereof will be prevented. The several stated objects, and other objects which will incidentally appear in the course of the following description, are attained in the use of such a device as is illustrated in the accompanying drawing, and the invention resides in certain novel 30 features which will be particularly pointed out in the appended claims.

In the drawing—

Figure 1 is a vertical section of a hot air furnace having my improved humidifying attachment fitted thereto;

Fig. 2 is an enlarged section of the attachment;

Fig. 3 is a detail plan view of the distributing reservoir.

The furnace may be of any desired construction and is illustrated as comprising an inner heating shell 1 and an outer casing 2 from which the heat-conducting flues extend, the inner heating shell 1 being provided at or near its upper end with a smoke flue 3 extending through the outer casing and connected with the chimney of the building in the usual manner. In carrying out my invention, I employ a boiler or generator 4 which may conveniently be a casting of metal and is closed except at its top where it is provided with an internally threaded opening 5 in which is secured the lower end of a pipe 6 which extends through 55 the top 7 of the furnace. To avoid leakage of smoke and gases at the point where the

said pipe passes through the furnace top, I fit upon the pipe a packing nut or collar 8 which is dished upon its upper side to receive a packing 9 of asbestos or other material. The packing nut or collar bears against the under side of the furnace top, as shown clearly in Fig. 2, and over the furnace top I mount a nut 10 upon the pipe 6 which nut is turned home against the top 65 of the furnace so as to firmly secure the pipe therein and compress the packing so that a tight joint will be provided. The pipe extends somewhat above the nut and upon the extremity of the pipe I secure the 70 distributing reservoir 11 which may conveniently be a metallic casting and which may be of any desired form or size. The top of this reservoir is open and across the same extends a central supporting bar 12 75 which may be permanently secured to the upper edges of the reservoir in any desired manner, preferably by welding. To the said supporting bar 12, I secure a canopy 13, preferably by welding, which canopy is 80 of less diameter than the reservoir so that a space will be provided between its edge and the sides of the reservoir to permit the escape of the vapor, and the canopy is preferably formed with a concave surface on its 85 under side so that any water which may be thrown against the same will be deflected to the sides of the reservoir and returned to the bottom thereof and prevented from flowing over the sides of the reservoir and 90 reaching the metallic shell of the furnace to corrode the same. The distributing reservoir is provided in its front side at such a height as experience may show to be most desirable with an opening 14 in which is 95 secured the inner end of a feed pipe 15 extending through the front wall of the furnace casing 2. The front end of this feed pipe 15 is connected with the receiving and overflow reservoir 16 by a coupling 17 100 threaded upon the front end of the pipe and upon a nipple 18 fitted in and projecting through the rear wall of the reservoir, the coupling serving to effect a tight joint by being turned home against the wall of the reservoir, as will be readily understood upon reference to Fig. 2. The reservoir 16 may be of any desired form and dimensions and is provided in its top wall with an inlet, preferably in the form of a funnel 19, through 110 which water may be admitted to the reservoir. Between the inlet and the rear wall

of the reservoir is a partition or baffle 20 which depends from the top of the reservoir and terminates between the nipple 18 and the bottom of the reservoir so that the water 5 admitted to the reservoir must flow under the edge of the baffle or partition to reach the feed pipe 15 in an obvious manner. An overflow pipe 21 is fitted in the bottom of the reservoir and may lead to a sewer or 10 other point of discharge and the upper end of this overflow pipe is disposed approximately in the horizontal plane of the axis of the feed pipe 15. A standard 22 is secured upon the receiving reservoir 16 and projects 15 above the top of the same, a valve 23 being supported by the said standard or bracket in communication with a supply pipe 24 which may be connected with the city water main or with a main supply tank if the 20 furnace is installed in a locality where there is no city water system. The valve 23 may be of any well-known form and is coupled with the pipe 24 by an elbow 25, the elbow serving to effectually clamp the valve casing 25 to the standard when the elbow is turned home against the side of the standard, as will be readily understood.

It is thought the operation of the device will be readily understood. The valve 23 30 is opened to such an extent as may be necessary to control the flow of water and permit the water to pass into the boiler or generator 4 with the desired rapidity. Obviously, the water will accumulate in the 35 receiving and overflow reservoir to the level of the pipe 15 and the overflow pipe 21 and will then flow through the pipe 15 into the distributing reservoir and from the said reservoir will pass down through the pipe 40 6 to the generator or boiler. The heat in the fire-box will play directly upon the bottom and sides of the generator and will, therefore, rapidly generate vapor or live 45 steam which will rise through the pipe 6 and the distributing reservoir and pass out around the edge of the canopy 13 to mingle with the hot air within the furnace casing 2 and be carried through the several hot air flues to the various rooms in the building. Should the fire get low or be 50 permitted to expire, the flow of water may be cut off by closing the valve 23, as will be readily understood, but if the extinguishment of the fire should not be noted, the 55 water will not overflow from the distributing reservoir 11 but will pass out through the overflow pipe 21 and will thereby be prevented from flowing onto the metallic shell of the furnace and corroding the joints 60 or any other parts of the same. The valve 23 should be set, of course, to permit the water to drip into the receiving and overflow reservoir or to pass into the same in a fine stream in such volume as may be needed 65 to maintain a supply of water in the gen-

erator but it should not be permitted to pass into the receiving reservoir in a greater volume than may be readily evaporated in the normal operation of the furnace. Obviously, the valve may be set to adjust the 70 flow to the vaporization so that the supply of water will be kept uniform in any given furnace. When the water is initially heated and ebullition occurs, the boiling water will tend to gush up from and over the distributing reservoir but, when this action occurs, the water so thrown up will strike against the under concave surface of the canopy 12 and will, consequently, be prevented from 75 passing out from the distributing reservoir 80 but will be turned back into the body of water therein, the vapor or steam, however, being permitted to escape around the edges of the canopy and mingle with the hot air flowing into the different rooms of the 85 building.

My device is obviously simple in the construction and arrangement of its parts; it may be fitted to any furnace now in use and may, of course, be supplied with furnaces to 90 be installed, and in actual practice has been found highly efficient for the purpose for which it is designed. It may be further noted that if the vaporization of the water occurs rapidly so that steam may pass 95 through the feed pipe 15 into the distributing and overflow reservoir 16, this steam will not reach the overflow pipe nor the supply pipe to interfere with the inflowing cold water but will be trapped between the 100 rear wall of said reservoir and the baffle or partition 20 and will be there condensed to return with the incoming water to be generated. The pressure exerted by this 105 trapped steam or vapor will also serve to accelerate the flow of the feed water to the generator.

Having thus described the invention, what is claimed as new is:

1. A humidifying attachment for hot air 110 furnaces comprising a generator to be supported in the fire box of the furnace, an open-top reservoir to be supported exteriorly of the fire box of the furnace and in communication with the generator, a supply pipe extending laterally from said open-top reservoir, a receiving reservoir secured on the outer end of the supply pipe, and means for supplying water in a constant retarded 115 regulated flow to said receiving reservoir. 120

2. A humidifying attachment for hot air 125 furnaces comprising a generator to be disposed within the fire-box of the furnace, a pipe carrying said generator, a distributing reservoir mounted on and in communication with said pipe, a feed pipe entering the side of the distributing reservoir, a receiving reservoir connected with the end of said feed pipe, a baffle depending from the top of the receiving reservoir in spaced relation to the 130

feed pipe and terminating between the end of said feed pipe and the bottom of the reservoir, an overflow pipe leading from the bottom of the said reservoir, and means for supplying water through the top of the reservoir in regulated quantities.

3. A humidifying attachment for hot air furnaces comprising a generator to be supported within the fire-box of the furnace, a pipe carrying said generator and in communication therewith, a distributing reservoir on said pipe having an open top, a baffle supported in the upper end of said distributing reservoir and having its edges spaced from the side walls of the reservoir, a feed pipe entering one side of said reservoir, a receiving reservoir connected with said feed pipe, a baffle within the receiving reservoir depending from the top of the same and having its lower end disposed between the end of the feed pipe and the bottom of the reservoir, an overflow pipe leading through the bottom of said reservoir in advance of the said baffle, an inlet in the top of the reservoir, the baffle being disposed between said inlet and the end of the feed pipe, and means for supplying water to said inlet in regulated quantities.

4. The combination with the body of a hot air furnace, of a pipe extending through the top of said body, a generator secured on the lower end of said pipe and in communication therewith and supported thereby in the fire-box of the furnace, a dished nut mounted on said pipe against the under side of the top of the furnace, packing fitted in the dished portion of said nut around the

pipe, a lock nut mounted on said pipe and turned home against the top of the furnace body, a distributing reservoir secured upon the upper end of the said pipe and open thereto, a baffle in the upper portion of the said distributing reservoir spaced from all the sides thereof, a feed pipe entering the front wall of said reservoir, a receiving reservoir connected with the front end of said feed pipe, and means for supplying water to the receiving reservoir in regulated quantities.

5. A humidifying attachment for hot-air furnaces comprising a generator to be supported in the fire-box of the furnace, an open-top reservoir to be supported exteriorly of the fire-box of the furnace and in communication with the generator, a baffle supported in the top of the reservoir with its edges spaced from the sides of the reservoir, and means for supplying water to said reservoir.

6. A humidifying attachment for hot-air furnaces comprising a generator to be supported in the fire-box of the furnace, a distributing reservoir to be supported exteriorly of the fire-box and in communication with the generator, a receiving reservoir in communication with the distributing reservoir, means for supplying water to the receiving reservoir in regulated quantities, and a baffle in the receiving reservoir preventing direct flow of water to the distributing reservoir.

In testimony whereof I affix my signature.

CLARENCE E. SALLADA. [L. s.]
